N° 874.

M. C. Burleigh's Design for the Doors & Panels of Stoves.

Patented March 10. 1857.

Dec. 874

M. C. Burleigh, of Great Falls, N. H.
Letters Patent No 874. Dated. Mar 10th 1857.

The schedule referred to in these Letters Patent and making part
of the same.

To all whom it may concern:

Be it known that I, M. C. Burleigh,
of Great Falls, in the County of Strafford, and State of New Hampshire,
have invented or produced a new and ornamental design
for the doors and panels of looking Stoves: and do hereby declare
that the following is a full, clear and exact description of the same,
reference being had to the annexed drawings, making a part of this
specification, in which

Fig. 1. is a front view of a stove door showing
my design.

Fig. 2. is a horizontal section of do. the plane
of section being through the centre.

Similar letters of reference indicate correspond-
ing parts in the two figures.

A represents a stove door of rectangular
form, and having inclined or beveled edges (a) (a). These inclined
or beveled edges are formed each of an ovoli bead (b) and two
obtuse quirks (c) (c), as shown clearly in Fig. 2.

The face or panel of the door, or the part en-
closed or comprised, within the inclined or beveled edges (a) (a), has
a bead (d) around it near its edges: said bead being semi-
cylindrical or half round, as shown clearly in Fig. 2.

At the centre of the face or panel there is
an ornament surrounded by an annular bead (e): said bead
having angular corrugations (f) projecting radially from it;
said corrugations forming a square as shown clearly in Fig.

The space within the annular bead (e) projects outward in curved form from the bead (e) towards its centre, as shown clearly in Fig. 2, and the projection at the centre of the space has an annular bead (f') formed on it, and a circular projection (g) is formed within the bead (f').

The ornament within the annular bead (e) is formed of nine bottle or flask-shaped prominences (h) which project radially from the central bead (f') and projection (g), as shown clearly in Fig. 1.

What I claim as new, and desire to secure by letters patent, is:

The central ornament within the annular bead (e), the angular corrugations (f), on the face or panel of the door, and the beads (d) around the edges of the panel, and the beveled or inclined edges of the door having the ovoli beads (b) upon them, and the obtuse quirks (c) (c); when the above parts are arranged and combined as herein shown and described, to form a new and ornamental design for a door or panel of a Cooking Stove.
